BATTERY TERMINAL CONNECTER

Henry A. Recen, Kokomo, Colo., assignor of one-half to Charles W. Burnheimer, Breckenridge, Colo.

Application May 25, 1937, Serial No. 144,625

3 Claims. (Cl. 173—259)

This invention relates to improvements in battery connectors of the type described and claimed in Patent No. 1,921,840, granted to me August 8, 1933.

5 Practically all automotive vehicles are provided with storage batteries and these must be removed from time to time for cleaning, charging and for other purposes.

It is well known that the ordinary connectors 10 are difficult to remove as the acid corrodes the clamping bolt and makes it practically impossible to rotate it in the nut, with the result that the connector has to be pried off from the battery terminal and is frequently ruined.

15 It is the object of this invention to produce a connector that can be readily applied to a battery terminal and which can as readily be removed when necessary.

Another object is to produce a connector of 20 such construction that there will be a wiping contact between it and the battery terminal when the connector is applied so that a good electrical contact will be established.

A further object is to produce a connector of 25 such construction that the part which performs the clamping action will be moved into position by the action of a screw and can thus be forced into operative position.

The above and other objects that will become 30 apparent as the description proceeds, are attained by means of a construction and an arrangement of parts that will now be described in detail and reference for this purpose will be had to the accompanying drawing in which the invention has 35 been illustrated in its preferred form and in which—

Figure 1 is a top plan view showing the connector in place on a battery terminal;

Figure 2 is a side elevation, looking in the direction of arrow 2 in Fig. 1;

Figure 3 is a section taken on line 3—3 Fig. 2;

Figure 4 is a section taken on line 4—4 Fig. 1;

Figure 5 is a top plan view of the connector showing the same detached from the battery terminal; and

Figure 6 is a section taken on line 6—6 Fig. 5.

In the drawing, reference numeral 7 designates the main body of the connector and numeral 8 a movable clamping member, while numeral 9 designates the battery terminal post and 10 the clamping screw.

The body 7 of the connector has one end provided with an opening 11 for effecting a connection with one end of a battery cable 12. Any

other means for effecting a connection with the cable may be substituted for the one shown.

The body of the connector is of the flattened oblong shape shown in the drawing and has an opening which has been designated by numeral 5 13.

That portion of the opening which is positioned above the line x—x Fig. 1 is the arc of a circle and in the embodiment illustrated it is a semi-circle. One wall of the opening has a straight section 14 that connects with an inwardly concave wall portion 15, whose surface approaches the center of the semi-circular end towards the right in Fig. 3. Positioned in the opening 13 is a clamping member 8, the outer end of which is curved on the same radius as the semi-circular end of the opening 13; this curved end wall has been designated by numeral 16. The inner end of the clamping member 8 has a deep notch 17 between the two flanges 18 and 19. The bottom of notch 17 is convex and engages the convex surface of wall 15 as shown in Fig. 3. It is evident that when the clamping member is moved along wall 15 from left to right in Fig. 3, the cylindrical surface 16 will move 20 towards the center of the semi-cylindrical portion of the opening 13, with the result that if the terminal 9 is in position, it will be subjected to pressure due to the wedging action of the clamping member 8 as it is moved towards the 25 right (Fig. 3). The clamping member has a screw 10 extending through an inclined threaded opening in the clamping member in such a position that its end engages the inner surface of wall 14 (see Figs. 1, 3, 5 and 6). When the screw 30 is rotated so as to move it towards the left in the opening in member 8, the latter will move towards the right and slide along the concave wall 15, thereby forcing the concave surface 16 against the battery terminal. The slight rotary 35 movement of surface 16 relative to the terminal 9 serves to effect a good electrical contact.

The upper surface of the connector has a flange 20 whose ends have been designated by numerals 21 and 22 and the head of the screw is so positioned that it will engage the end 21 when the clamping member 8 is moved outwardly as in Fig. 5, and thus prevent the clamping member from falling out during shipment. It will be noted that the end 21 of flange 20 functions as a stop. 45

Since the end of the screw abuts the wall 14, it will move the clamping member towards the right, but will itself remain transversely stationary.

In the patent above identified, there is a clamp- 55

ing member that corresponds to the clamping member 8 of the present invention, but it is intended to be turned by hand or by means of impacts from a hammer or in some such way. In 5 the present device, the movement is forced by the action of the screw 10. Attention is also called to the construction that prevents the clamping member from falling out during shipment.

10 Let us now assume that we have a connector and desire to attach the same to a battery terminal 9. Screw 10 is turned so as to withdraw it from the opening in member 8 until its end is flush with the wall of the member and the 15 latter is moved towards the left as far as it will go. Terminal 9 is now inserted in opening 13, after which the screw is turned so as to effect a movement of member 8 towards the right, thereby wedging the terminal between the surface 16 20 and the end of opening 13. When the connector is to be removed, the screw is turned so as to withdraw its end from wall 14, after which the clamping member can be tapped with a hammer and moved towards wall 14, thereby releasing the 25 pressure on the terminal.

The parts may, of course, be covered with lead in the usual manner.

The invention, although it has been described as a battery terminal connector, is also suitable 30 for other uses, as for example, telephone and radio ground connectors and electrical connectors generally, and the uses pointed out are for the purpose of illustration only.

Having described the invention what is claimed 35 as new is:

1. A battery terminal connector having one end provided with means for making connection with a cable and the other end provided with an opening for the reception of a battery terminal 40 post, the opening having a portion of its wall formed by a semi-cylindrical surface and another portion by a concave surface opposed to the semi-cylindrical surface and eccentric with relation to the latter, a clamping member positioned in 45 the opening, provided with a concave surface facing the semi-cylindrical surface and a convex surface for engaging the eccentric concave surface and for movement therealong, and means comprising a screw, threadedly associated with 50 and extending through the clamping member for engaging the wall of the opening in the connector, to push the clamping member along the concave eccentric surface in a direction to de-

crease the distance between the concave surfaces on the clamping member and the semi-cylindrical surface on the connector.

2. A battery terminal connector having one end provided with means for making connection with a cable and the other end provided with an opening for the reception of a battery terminal post, the opening having a portion of its wall formed by a semi-cylindrical surface and another portion by a concave surface opposed to the semi-cylindrical surface and eccentric with relation to the latter, a clamping member positioned in the opening, provided with a concave surface facing the semi-cylindrical surface and a convex surface for engaging the eccentric concave surface and for movement therealong, means comprising a screw, threadedly associated with and extending through the clamping member for engaging the wall of the opening in the connector to push the clamping member along the concave eccentric surface in a direction to decrease the distance between the concave surfaces on the clamping member and the semi-cylindrical surface on the connector, and means comprising the screw and a cooperating stop on the connector for holding the clamping member in the connector.

3. A battery terminal connector having one end provided with means for making connection with a cable and the other end provided with an 30 opening for the reception of a battery terminal post, the opening having a portion of its wall formed by a semi-cylindrical surface and another portion by a concave surface opposed to the semi-cylindrical surface and eccentric with 35 relation to the latter, a clamping member positioned in the opening, provided with a concave surface facing the semi-cylindrical surface and a convex surface for engaging the eccentric concave surface and for movement therealong, 40 means comprising a screw extending through and threadedly connected with the clamping member engaging the connector and pushing the clamping member along the concave eccentric surface in a direction to approach the semi-cylindrical surface, and means comprising a 45 flange on the clamping member, a stop on the connector, and a screw carried by the clamping member in position to engage the stop, for limiting the movement of the clamping member in 50 one direction and for holding the clamping member from removal.

HENRY A. REGEN.
